UNITED STATES PATENT OFFICE.

LEONARD S. BEALS, OF ASTORIA, NEW YORK.

DESIGN FOR JEWELRY DROP OR PENDANT.

Specification forming part of Design No. 7,924, dated December 15, 1874; application filed November 28, 1874.
[Term of Patent 3½ years.]

CASE No. 2.

To all whom it may concern:

Be it known that I, LEONARD S. BEALS, of Astoria, in the county of Queens and State of New York, have invented a Design for Drop, of which the following is a specification:

The nature of my design is fully represented in the accompanying drawing, to which reference is made.

The jewelry drop or pendant A is formed in imitation of a flower, with a central button, a, resembling the seed of a *nasturtium*, from the base of which project a series of small leaves, b.

What I claim as new, and desire to secure by Letters Patent, is—

The design for a jewelry drop or pendant, as shown and described.

In testimony that I claim the foregoing I have hereunto set my hand and seal this 24th day of November, 1874.

LEONARD S. BEALS. [L. S.]
